UNITED STATES PATENT OFFICE.

L. SOLON GROUT, OF CHICAGO, ILLINOIS.

DESIGN FOR A WATCH-MAKER'S SIGN.

SPECIFICATION forming part of Design No. 17,213, dated March 29, 1887.

Application filed February 18, 1886. Serial No. 192,464. Term of patent 7 years.

To all whom it may concern:

Be it known that I, L. SOLON GROUT, a citizen of the United States of America, residing at Chicago, in the county of Cook and State of Illinois, have invented and produced a new and original Design for Watch-Makers' Signs, of which the following is a specification, reference being had thereto to the accompanying drawing.

10 The drawing represents a face view of the sign, the leading features of which are a rhombus or diamond shaped sign-plate, in the center of which the design of a stem-winder watch is represented in bas-relief, and in a pair of 15 spectacles having rhombus or diamond shaped glasses depended from such sign-plate.

A denotes a flat plate, being in outline rhombus or diamond shaped, and having a representation of a rope molding for a border 20 or around its edges, with ears b c. Upon the center of this plate A is brought out in bas-

relief the representation of a watch, d, having a convex dial. Upon the margin around the watch, and within the border, is a space, as shown. Below the watch-sign is depended a 25 pair of spectacles, B, having rhombus or diamond shaped glasses.

What I claim is—

The design of a watch-maker's sign herein shown and described, the same consisting of 30 the rhombus or diamond shaped sign-plate having upon it the representation of a watch and having suspended to its bottom the representation of a pair of spectacles with diamond or rhombus shaped glasses. 35

In testimony whereof I affix my signature in presence of two witnesses.

L. SOLON GROUT.
